UNITED STATES PATENT OFFICE.

CHARLES NELSON, OF NEW YORK, N. Y., ASSIGNOR TO S. STERNAU & COMPANY, OF NEW YORK, N. Y., A COPARTNERSHIP.

DESIGN FOR A COFFEE-PERCOLATOR.

42,088.

Specification for Design.

Patented Jan. 9, 1912.

Application filed July 11, 1910. Serial No. 571,513. Term of patent 7 years.

To all whom it may concern:

Be it known that I, CHARLES NELSON, a citizen of the United States, and a resident of the borough of Brooklyn, county of Kings, city and State of New York, have invented a new, original, and ornamental Design for Coffee-Percolators, of which the following is a specification, reference being had to the accompanying drawing, forming part thereof.

The figure is an elevation of a coffee percolator showing my new design.

The design comprises a cover 1 of pyra-

midical shape, a cylindrical body 2 with square handles and a stand 3 having square legs with pediments and feet of square shape and a square top 4. The design comprises the conformation of the parts and not their lack of ornamentation.

I claim:

The ornamental design for a coffee percolator, as shown and described.

CHARLES NELSON.
